UNITED STATES PATENT OFFICE.

EDWARD B. PEIRCE, OF LOWELL, MASSACHUSETTS.

WHEELBARROW.

1,052,953.

Specification of Letters Patent.

Patented Feb. 11, 1913.

Application filed May 23, 1911. Serial No. 628,941.

To all whom it may concern:

Be it known that I, EDWARD B. PEIRCE, a citizen of the United States, residing at Lowell, in the county of Middlesex and 5 Commonwealth of Massachusetts, have invented a certain new and useful Improvement in Wheelbarrows, of which the following is a specification.

This invention relates to wheelbarrows, 10 such as are designed chiefly to be run on a permanent or temporary rail, as in the construction and repairing of railways and in railway freight-yards on the track-rails or in mining tunnels or tracks or on any rough 15 or soft ground where portable rails may be laid.

In a previous Patent, No. 674,710, granted to me May 21, 1901, I showed and described a wheelbarrow having a single wheel peripherally-grooved to receive a rail, said 20 wheel being so swiveled as to be capable of being turned at such an angle with the line of draft or travel of the wheelbarrow as to permit the barrowman while propelling the 25 barrow to walk at one side of the rail instead of straddling the rail. In the wheelbarrow herein shown and described, I accomplish the same result by other means and wholly 30 relieve the barrowman from the weight of the load. To this end, I arrange two such grooved supporting wheels in the same vertical longitudinal plane, in which lies the 35 normal center of gravity of the barrow and load, and I place the center of gravity of the tray of the barrow very low, so that it is very easy for the barrowman to maintain 40 said barrow and load in an upright position and to reserve his strength for the propelling of the barrow on the rail, and I arrange the 45 handle-bars in such a manner that their free ends are in a position to enable the barrowman to walk at the side of the supporting rail. I have also provided the barrow with a pair of connected legs pivoted in such a 50 manner as to be easily brought into or out of use by the hand or foot of the barrowman.

In a modified form of my invention, I show means by which the handles may be 55 adjustable to either the right or left side of the line of draft of the barrow; also how the median line of the handle-bars may be brought into alinement with the line of travel where occasion requires the barrow to be used on surfaces, as the floors of

freight-houses, where a rail may not be 55 needed.

In the accompanying drawing on three sheets, Figure 1, is a right side elevation of a wheelbarrow provided with my improvement; Fig. 2, a reversed plan of the same; 60 Fig. 3, a rear end elevation of the same, the legs of the barrow being represented as in use in Fig. 3, but not in the preceding figures. In the above named figures, the handles are represented as laterally offset 65 and permanently secured in place. In Figs. 4-8 the handles are represented as equally adjustable in opposite directions to enable the barrowman to walk on either side of the rail. Figs. 4 and 5 are respectively a rear 70 elevation and a side elevation of the wheelbarrow supported on a rail; Fig. 6, a vertical section, on the line 6 6 in Fig. 4, of the means of adjusting the handle-bars; Fig. 7, a rear elevation of said adjusting means, the 75 swivel-plate being partly in section on the line 7 7 in Fig. 8; Fig. 8, a plan of said adjusting means, the barrow being in section on the line 8 8 in Fig. 4. The remaining 80 Figs. 9, 10 and 11 show a modification of the means for adjusting the handle-bars and are respectively a side elevation, a reversed plan 85 and a rear elevation, the handle-bars in Fig. 11 being in vertical transverse section on the line 11 11 in Fig. 10.

A indicates the tray or scoop of the barrow (Figs. 1-8), to which are secured parallel frame-bars B B¹, in which are supported the horizontal axles c c¹ of the wheels C C¹, said frame-bars extending beyond the tray A in front and rear, to allow 90 said tray to be placed between the wheels and to bring the center of gravity of said tray and load very low. The bars B B¹ are preferably of angle-iron and their end-portions are bent upward and secured to the scoop by rivets b b¹ or equivalent means. 95

The wheels C C¹ are provided with peripheral grooves c² c³ to receive a rail which may be either a permanent rail D, of the 100 ordinary construction, supported on sleepers d which rest upon the ground E in the usual manner, or a temporary or portable rail which may consist of a flexible pipe or rod, as stated in said previous patent. The 105 wheels C C¹ are arranged tandem, that is, in the same vertical longitudinal plane which passes through the center of gravity

of the tray and of an evenly distributed load in said tray, so that, the center of gravity being very low, it is an easy matter to maintain the barrow in a vertical position.

5 A bar F is bent to the shape best shown in Figs. 2 and 3, having a straight middle portion which passes through the bars B B¹ and is journaled therein in front of the rear wheel C and is then bent backward at f¹ f² parallel with said bars for a distance and then spread outwardly at f³ f⁴, to form legs which, being turned vertically downward, are long enough to reach the ground or 10 track on each side of the rail D when the wheels are on the rail, and when turned down to a less extent, will support the barrow when the wheels rest upon the ground. The legs are held in the desired position by 15 a latch G pivoted at g to one of the parallel parts, as f¹, of the bar F and provided with notches g² g³ g⁴ so arranged that when the lower notch g⁴ is in engagement with the guide and catch-plate G¹, secured to the 20 rear of the tray, the legs are wholly out of contact with the ground; when the next notch g³ is in such engagement, the legs reach the ground when the barrow is on the ground; and when the upper notch g² is in 25 such engagement, the lower end of the legs rest upon the ground when the wheels are on the rail. When the legs are in the raised position shown in Fig. 1, the barrowman may disengage the latch G by pushing it 30 forward with his foot, without letting go of the handles of the barrow, and the legs will fall by their own gravity until they touch the ground. The upper end of the latch being provided with a hook g⁵ the latch may 35 be lifted raising the legs by hand or by the 40 foot applied to said hook.

In Figs 1-3, the handle-bars H H¹ are rigidly secured to the tray of the barrow by means of bolts h for equivalent devices and 45 by straps h¹ in an obvious manner, but the free ends of the handles h² h³ proper of said bars, instead of being arranged symmetrically or at equal distances from the median plane of the wheelbarrow, are offset toward 50 one side of the barrow sufficiently to enable the barrowman grasping said handles to walk by the side of the rail on which the barrow runs. In the remaining figures, the handles are represented as adjustable laterally in either direction, to allow the barrowman to walk on either side of the rail as 55 necessity may require or as may suit his convenience.

In Figs. 4-8, the handles H² H³ are supported on a swivel-plate I which turns on a central pivot i, rigidly secured to the back of the tray A in such a manner that the upper portion of the handles, which are arranged considerably above said center, may 60 be turned to the right or the left. The plate 65

I is provided with an arc-shaped marginal flange i¹ provided with holes i² i³ i⁴ arranged radially therein and each adapted to receive a pin J, which being passed through a bracket K, secured to the back of the tray 70 above said plate, locks said swivel-plate with the handles at equal distances from the median plane when said pin is in the hole i³, or laterally displaced to the left when said pin is in the hole i², or to the right when said pin is in the hole i⁴. Said pin J is hung to the front of the tray by a chain j to prevent its being lost or out of place when wanted. The handles H² H³ are not rigidly secured to the plate I but are arranged in 75 sleeves k¹ k² fixed on said plate, in which they may be separately adjusted, to vary their height and when adjusted, said handles are held from movement in any direction by spring-latches k⁰ k which are represented as leaf-springs each having one end riveted at k² k³ to one of said sleeves and near the other or free end provided with a pin k⁴ k⁵ which passes through a hole in the corresponding sleeve and into one of several 80 holes k⁶ with which the lower part of each handle-bar is provided, thus preventing said handle-bars from turning or moving longitudinally in said sleeve.

In Figs. 9-11 the handle-bars H⁴ H⁵ are 85 represented as both formed in one piece and pivoted at their common front end to a cross-bar B³ secured to the frame-bars B⁴ B⁵, said handle-bars diverging rearwardly and extending about parallel with the bottom of the tray for some distance and being off-set upwardly to a suitable height to enable their rear ends or handles proper to be conveniently grasped by the barrow-man. The handles are guided between parallel 100 cross-bars B⁶ B⁷, secured to the frame-bars B⁴ B⁵ near the rear of the bottom of the tray, and may be moved laterally between said cross-bars to bring the barrowman at either side of or directly behind the middle 105 of the tray. When the handle-bars are swung to the right or left they are retained in place by the right or left handle-bar engaging a notch or bend b³ or b⁴ in the upper one B⁶ and being retained therein by the 110 weight of the tray and its load.

In Figs. 9-11 the barrow is represented as provided with permanent legs F¹ F² which reach down at all times below the rear wheel of the barrow, as shown in Figs. 110 9 and 11, said rear wheel C being represented as smaller than the front wheel C¹, so that the barrow may be used on the ground without a rail in the usual manner, the wheels being however grooved to receive a 115 rail as above described. The legs F¹ F² consist of bars bent as shown and secured at their front ends to the cross-bar B³ and at their rear ends to the cross-bar B⁷.

In the last-named figures the tray is rep- 130

resented as provided with sockets **L** to receive stakes which may be used in the ordinary manner to retain in place bars, sleepers or such articles arranged transversely 5 of the tray between said stakes. The small rear wheel **C** in the figures last-named is represented as supported in a strap **M** bent upward like an inverted **U** and secured to the cross-bar **B'**, said strap having laterally 10 extended arms **m m'** secured to the legs **F' F''** at their outer ends.

I claim—

1. The combination in a wheelbarrow, of a frame, two wheels, each provided with a 15 peripheral groove to receive a rail, said wheels being arranged tandem and having handles arranged at unequal distances from the median plane of said barrow.
2. The combination in a wheelbarrow, of 20 a frame, two wheels, each provided with a peripheral groove, said wheels being arranged in the same vertical plane and a

pair of handles, the median line of which is at an angle with the path of travel of said wheelbarrow, to enable the barrowman 25 to walk at one side of said rail while propelling the barrow with both wheels on said rail.

3. The combination in a wheelbarrow, of a frame, two wheels arranged in the vertical median plane of said wheelbarrow and each provided with a peripheral groove to receive a rail and a pair of handles and means of adjusting said handles laterally so that their median line shall form an 30 angle with the line of travel of said wheelbarrow.

In witness whereof, I have affixed my signature in presence of two witnesses.

EDWARD B. PEIRCE.
